CLAIM

The ornamental design for a ceramic heater as shown and described.

DESCRIPTION

FIG. 1 is a perspective view of overall shape of a ceramic heater showing my new design,

FIG. 2 is a front view thereof,

FIG. 3 is a rear view thereof,

FIG. 4 is a left side view thereof,

FIG. 5 is a right side view thereof,

FIG. 6 is a top plan view thereof; and,

FIG. 7 is a bottom plan view thereof.

The broken lines shown in the drawings illustrate portions of the ceramic heater that form no part of the claimed design.

1 Claim, 7 Drawing Sheets
